PUMP OR MOTOR CONSTRUCTION

Lawrence M. Persons, Des Moines, Iowa, assignor
to Penn Electric Switch Co., Des Moines, Iowa,
a corporation of Iowa

Application October 9, 1933, Serial No. 692,805

3 Claims. (Cl. 103—174)

An object of my invention is to provide a device which can be used either as a pump or a motor, yet which is of simple, durable and inexpensive construction.

5 Another object is to provide a pump or motor construction of improved design over my copending application, Serial No. 631,892, filed September 6, 1932, of which the present application is a continuation in part.

10 A further object is to provide a pump or motor construction in which radially arranged cylinders have pistons therein with their heads toward each other and a crank shaft is journaled among the cylinders and has connecting rod means of connection with pins which extend laterally from the outer ends of the pistons, the cylinders being slotted for said pins.

15 A further object is to provide radially arranged cylinders which are offset from radial lines so that where the heads of the cylinders come together, a minimum of space can be provided so that there is a minimum travel of pumped or operating fluid from a valve in said space.

20 A further object is to provide the crank shaft journaled in such space and constituting a rotary valve for the control of pumped or operating fluid to and from the cylinders of the device.

25 Still another object is to provide a pump for compressing air, for instance, which is extremely quiet in operation and has a minimum number of working parts.

30 With these and other objects in view my invention consists in the construction, arrangement and combination of the various parts of my device, 35 whereby the objects contemplated are attained, as hereinafter more fully set forth, pointed out in my claims, and illustrated in the accompanying drawings, in which:

35 Figure 1 is a sectional view through a pump or motor construction embodying my invention, such as shown in my copending application hereinbefore referred to.

40 Figure 2 is a sectional plan view on the line 2—2 of Figure 1.

45 Figure 3 is an enlarged sectional view on the line 3—3 of Figure 1.

50 Figure 4 is a front elevation of my improved form of pump or motor construction, a part of the casing being broken away to better illustrate the construction of the pump.

55 Figure 5 is a vertical sectional view on the line 5—5 of Figure 4.

Figure 6 is a sectional view on the line 6—6 of Figure 5 showing the parts on a reduced scale.

55 Figure 7 is a sectional view on the line 7—7 of

Figure 5 showing the parts on an enlarged scale; and

Figure 8 is a perspective view of a crank shaft used in my pump or motor construction.

On the accompanying drawings, I have used 5 the reference numeral 10 to indicate generally a motor casing for enclosing an electric motor, such as shown in my copending application. This casing forms no part of my present invention except that it has a crank shaft bore 12 and cylinder 10 bores 14.

Each cylinder bore 14 has therein a piston 16 and each piston has a laterally extending wrist pin 18. Each cylinder bore is provided with a slot 20. The slots 20 are provided for the pins 15 18, as clearly shown in Figure 3.

A crank shaft 22 is journaled in the crank shaft bore 12 and is provided with a crank disk 24. A crank pin 26 extends from the crank disk 24. A pair of spaced washers 28 is journaled on 20 the crank pin 26.

A master connecting rod 30 is secured rigidly to the washers 28 by riveting or the like, while secondary connecting rods 32 are freely pivoted thereto. The outer ends of the connecting rods 25 30 and 32 are pivoted to the wrist pins 18.

It will be obvious that rotation of the crank shaft 22 will reciprocate the pistons 16, or that compressed air, oil under pressure or the like introduced into the cylinders 14 to cause the 30 pistons 16 to reciprocate will rotate the crank shaft 22.

For controlling the flow of compressed air, oil under pressure or the like to and from the cylinders 14, I provide for each cylinder head a 35 port 34. Depressions 36 and 38 are milled into the crank shaft 22 for providing timed communication between the oil in a storage compartment 40, the cylinders 14 and an outlet compartment 42.

40 In the position shown in Figure 1, oil is entering the left hand cylinder 14 and leaving the right hand cylinder by way of a countersunk portion 44. The construction in Figure 1 is thus used as a pump for pumping oil from the storage 45 compartment 40 to the compartment 42 from which it flows, as described in my copending application, into the operating cylinder of a valve. The pump of course can be used for other purposes however and can be used as a motor by 50 introducing oil under pressure, compressed air or the like into either the compartment 40 or 42.

The foregoing description is of a very small pump having cylinders one quarter inch in diameter for instance. The pump can be made on 55

any scale however and Figures 4 to 8 inclusive show the construction applied on a larger scale. Many of the parts are similar and accordingly will be given the same reference numerals with the addition of the distinguishing characteristic *a*.

Certain differences and improvements will now be described. The crank disk 24a is counterbalanced as at 25. This makes a smoother operating pump or motor. Instead of being solid, the pistons 16a are hollow to reduce weight and are provided with piston rings 17 to prevent undesired leakage.

The master connecting rod 30a has an extension 31 surrounding the crank pin 26a, thus positively preventing any rotation of the washers 28a independent of the master connecting rod 30a.

The intake port 36a of the crank shaft 22a communicates with an annular groove 37 with which a port 39 communicates. The outer end of the port 39 communicates with the interior of a casing member 41 which encloses the pump or motor and which is adapted to contain oil so that the device will at all times be effectively lubricated, the casing being carried approximately one fourth full of oil. A port 39a in the casing 41 admits air to the port 39.

The outlet port 38a communicates with a counter bore 43 of a hub 45 on the base plate 10a. An outlet pipe 47 communicates with the counter bore and compressed air or the like is pumped out through this pipe. A packing gland 49 is provided to prevent leakage around the crank shaft 22a.

The ports 36a and 38a, it will be noted, extend at an angle through the crank shaft so as not to interfere with each other. The cylinders, as shown in Figure 6, are offset from radial lines so that there is a minimum of space among them for the combined crank shaft and valve. This is an important feature, as in compressing air it is desirable that the head space be at a minimum in order to get maximum compression.

The particular arrangement of cylinders with their heads toward each other and having slots for laterally extending wrist pins is a novel and satisfactory construction where too great a pressure on the parts is not required. The particular arrangement of elements relative to each other

provides an inexpensive construction yet one which operates efficiently.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In a device of the class described, a casing having an air inlet, a plurality of radiating cylinders therein having heads adjacent each other, a piston in each cylinder, each cylinder having a slot in the side thereof, each piston having a pin 15 extending through each slot, a crank shaft, a hub therefor mounted on said casing and connecting rods connecting said pins with said crank shaft, said crank shaft having ports for controlling the flow of fluid through said inlet to said 20 cylinders and from said cylinders through said hub.

2. In a device of the class described, a casing, a plurality of radiating cylinders therein having heads adjacent each other, a piston in each cylinder, each cylinder having a slot in the side thereof, each piston having a pin extending through each slot, a crank shaft, a hub therefor mounted on said casing, said casing and hub having passageways, one an intake passageway and the 30 other an outlet passageway, and connecting rods connecting said pins with said crank shaft, said crank shaft having ports for controlling the flow of fluid through said inlet passageway to said cylinders and from said cylinders through said 35 outlet passageway.

3. In a device of the class described, a plurality of radiating cylinders having heads adjacent each other, a piston in each cylinder, each cylinder having a slot in the side thereof, each piston having a pin extending through each slot, a crank shaft, a hub connected with said cylinders, said hub having inlet and outlet passageways and connecting rods connecting said pins with said crank shaft, said crank shaft having ports for controlling the flow of fluid through said inlet passageway to said cylinders and from said cylinders through said 40 outlet passageway.

LAWRENCE M. PERSONS.
